US00D576030S

(12) **United States Design Patent**
Lee et al.

(10) **Patent No.:** **US D576,030 S**
(45) **Date of Patent:** **** Sep. 2, 2008**

(54) **CABLE DISPLAY PACKAGE**

(75) Inventors: **Noel Lee**, Las Vegas, NV (US);
Kendrew Lee, San Jose, CA (US);
Jacky Hsiung, San Jose, CA (US)

(73) Assignee: **Monster Cable Products, Inc.**,
Brisbane, CA (US)

(**) Term: **14 Years**

(21) Appl. No.: **29/299,430**

(22) Filed: **Dec. 26, 2007**

(51) LOC (8) Cl. **09-03**

(52) U.S. Cl. **D9/415; D9/425**

(57) **CLAIM**

The ornamental design for a cable display package, as shown and described.

DESCRIPTION

A portion of the disclosure of this patent document contains material which is subject to copyright protection. The copyright owner has no objection to the facsimile reproduction by any one of the patent document or the patent disclosure, as it appears in the Patent and Trademark Office patent file or records, but otherwise reserves all copyright rights whatsoever.

FIG. 1 is a perspective view of a cable display package, showing our new design;

FIG. 2 is a front elevation view thereof;

FIG. 3 is a rear elevation view thereof;

FIG. 4 is a side elevation view thereof;

FIG. 5 is a side elevation view of the opposite side view shown in FIG. 4;

FIG. 6 is a top plan view thereof; and,

FIG. 7 is a bottom plan view thereof.
